Inventor

Bernard C. Harloff

By his Attorney
George C. Heinricke

UNITED STATES PATENT OFFICE.

BERNARD C. HARLOFF, OF RICHMOND HILL, NEW YORK

REINFORCED-CONCRETE SLAB.

Application filed October 15, 1927. Serial No. 226,392

This invention relates to improvements in reenforced concrete slabs and method of making the same, and it is the principal object of my invention to make such a slab 5 having a beveled edge and equipped with means for allowing the passage of fastening means such as screws for securing the slab to a suitable support.

Another object of my invention is the provision of a novel and improved method of 10 making such slabs according to which the edges of the slab are beveled or formed so as to allow a ready removal of the slab from its form even in semi-plastic conditions without danger of having the slab 15 sticking to its form and thus damage the same.

A further object of my invention is the provision of a novel method of making re-enforced concrete slabs according to which the reenforcing wire screen etc., will float 20 in the form and thus be embedded in the body of the concrete at a certain distance from its sides.

25 These and other objects and advantages of my invention will become more fully known as the description thereof proceeds and will then be more specifically defined in the appended claim.

30 In the accompanying drawing, forming a material part of this disclosure.

Figure 1 is a perspective view of a reinforced concrete slab constructed according to my invention.

35 Figure 2 shows in section a mould used to form my concrete slab and illustrates one of the steps of my improved method of making such slabs.

Figure 3 is a view, similar to Figure 2, 40 and illustrates another step of my improved method.

Figure 4 is a fragmentary sectional view, illustrating the securing of two adjoining slabs to a beam.

45 Figure 5 is a bottom plan view thereof. As illustrated, the reenforced concrete slab 10 according to my invention has bevelled outer edges 11 and an inner reenforcing wire screen 12 embedded into the material thereof.

At certain points, preferably near its

outer edges, the slab is equipped with oppositely disposed sockets 13, having outwardly projecting annular flanges 13' formed on the upper portion thereof and 55 embedded in and flush with the upper face of said slab, said sockets being spaced from each other for the reception of screws 14 or the like fastening means for securely attaching the slabs to their supporting beams 60 15 or the like.

As illustrated in Figures 2 and 3 the concrete slabs according to my invention are made in moulds 16 the side-bars 17 of which have inner, oppositely disposed beveled 65 edges 18, which facilitates the removal of the finished slabs from their moulds.

According to my invention the reenforcing screen 12 is laid upon the mould bottom 16 and then the plastic concrete mass 70 is poured into the mould, so that the screen will float within this mass as clearly illustrated in Figure 3 and thus during the hardening process becomes firmly embedded into the slab at a certain distance from its 75 lower side. Suitable washer plates 19 are interposed between the screw heads and slab bodies.

From the above description it will be clear that I have invented a reenforced concrete slab which can be economically and cheaply manufactured by unskilled labor, a slab which does not stick to the form on account of its beveled edge, and which can be taken out of the form when still in semi-plastic condition, just as soon as it has sufficiently set.

It will be understood that such changes may be made in the general construction and in the method of making my novel and 90 improved reenforced concrete slab as come within the scope of the appended claim without departure from the spirit of my invention, and the principle involved.

Having thus described my invention what 95 I claim as new, and desire to secure by Letters Patent is:

A reenforced concrete slab of the class described comprising a body, beveled outer edges formed with said body, a reenforcing 100 screen between the sides of said body embedded into the same, a plurality of sockets

allowing the passage of fastening screws embedded in the slab near its side edges, outwardly projecting annular flanges formed on the upper edge of said sockets 5 embedded in and flush with the upper face of said slab and washers interposed between said mouth pieces and the heads of

the fastening screws the reenforcing screen surrounding said sockets.

Signed at New York in the county of 10 New York and State of New York this 13th day of October, A. D. 1927.

BERNARD C. HARLOFF.
